No. 878,953.

PATENTED FEB. 11, 1908.

H. K. HESS.
MOTIVE POWER.

APPLICATION FILED MAR. 23, 1903.

UNITED STATES PATENT OFFICE.

HENRY K. HESS, OF PHILADELPHIA, PENNSYLVANIA.

MOTIVE POWER.

No. 878,953.

Specification of Letters Patent.

Patented Feb. 11, 1908.

Application filed March 23, 1903. Serial No. 149,118.

To all whom it may concern:

Be it known that I, HENRY K. HESS, of Philadelphia, in the county of Philadelphia, in the State of Pennsylvania, have invented 5 new and useful Improvements in Motive Power, of which the following, taken in connection with the accompanying drawings, is a full, clear, and exact description.

This invention relates to improvements 10 in motive power which is particularly applicable for the propulsion of automobiles and other carriers.

In the use of gas engines for propelling vehicles as well as for various other uses the 15 exhaust or spent gases are usually discharged to atmosphere and it is well known that these gases escape from the engine in a highly heated condition, which, of course, represents a large percentage of energy.

20 The object of my invention is to utilize this heat to generate steam in a suitable boiler provided therefor and to further utilize the steam thus generated for the operation of a steam engine which is also connected to 25 propel the vehicle and may be used either independently or jointly with the gas engine.

Further objects will appear in the subsequent description.

In the drawings—Figure 1 is a top plan 30 of a running gear of a vehicle showing gas and steam engines, and a boiler operatively mounted upon the vehicle and connected together in a manner hereinafter described. Fig. 2 is a longitudinal vertical section 35 through the boiler and gas engine showing the steam engine in elevation and the connections between the engine and boiler. Fig. 3 is a longitudinal section of a portion of the rear driving shaft and adjacent portion of the supporting frame or bearings. 40 Figs. 4 and 5 are sectional views taken respectively on lines 4—4 and 5—5, Fig. 3.

Similar reference characters indicate corresponding parts in all the views.

45 In carrying out the objects of this invention I have shown a running gear of a vehicle comprising a frame —1— and front and rear axle sections —2— and —3—, said running gear being adapted to support a suitable body, as —4—, shown by dotted lines in Fig. 2.

Mounted upon the vehicle in any desired manner, not necessary to herein illustrate or describe, is a boiler —5—, a gas engine —6— 50 and a steam engine —7—, the boiler —5— being of the usual steam generator type hav-

ing a sub-chamber —8—, a smoke chamber —9— and connecting flues —10—. The gas engine —6— may also be of any desired construction having an explosion chamber —11— and a water jacket —12—, the explosion chamber being provided with an exhaust port —13— which is connected by a conduit —14— to the sub-chamber —8— of the boiler —5— in such manner that the heated spent gases escaping from the explosion chamber of the gas engine are conducted into the chamber —8— for the purpose of generating steam in the boiler —5—. This conduit —14— is inclosed by a shell —15— which is somewhat larger than the conduit —14— for forming a chamber —16— and forming a water jacket around the conduit —14—, one end of the chamber —16— communicating with the water jacket —12— of the cylinder of the gas engine, said water jacket —12— being provided with a supply pipe —17— through which cold water may be introduced, not only into the water jacket —12—, but also into the chamber —16—.

It will be understood that the water in the jacket —12— becomes heated by the ignited gases in the cylinder and by surrounding the conduit —14— with a water jacket communicating with the jacket of the cylinder the heat is communicated to the water in the chamber —16— and therefore acts as an auxiliary heating device for the water passing through the conduit —15—. In like manner I connect the water jacket —12— with the interior of the boiler by the conduits —19— and —20— so that the heated water from the jacket —12— will pass directly into the boiler for additionally heating the water therein.

95 The superimposed chamber —9— at the top of the boiler is provided with an outlet conduit —21— and the exhaust from the steam engine —7— is also discharged into this pipe —21— by a conduit —22— which is deflected downwardly and when the steam engine is in operation facilitates the draft through the flues —10—.

105 Steam is supplied to the engine —7— from the boiler through a conduit —23— having a throttle valve —24— which is controlled by a manually operated lever —25—, this valve and its operating lever being of any well known construction, not necessary to further illustrate or describe.

110 It is desirable to provide means for auto-

matically controlling the operation of the steam engine by the pressure of steam from the boiler, and I therefore, provide a second steam conduit —26— with a valve —27—, 5 the opposite ends of the conduit —26— being connected to the conduit —23— at opposite sides of the valve —24— and the valve —27— is located in the conduit —26— between its opposite ends and is connected 10 to a piston —28— which is movable in a cylinder —29— against the action of a spring —30—, said cylinder being connected to the conduit —23— at a point between the valves —24— and —27— and the steam 15 chamber of the boiler by an additional conduit —31— so that the cylinder is always in direct communication with the steam chamber of the boiler. The piston —28— is located between the steam inlet of the cylinder —29— and spring —30— and receives 20 the impact of the steam pressure from the boiler, the spring —30— acting upon the piston against the steam pressure to hold said piston in its normal position, in which position the valve —27— of the conduit —26— is closed.

When it is desired to operate the engine —7— automatically the valve —24— is closed so that the steam passes directly into 30 the conduits —26— and —31—, the valve —27— being normally closed and preventing the passage of the steam to the engine and when the steam pressure is sufficient to overcome the tension of the spring —30— the 35 piston —28— is moved against the action of the spring to open the valve —27—, which may be of any desired construction not necessary to herein illustrate or describe, and the steam, therefore, passes through the 40 valve —27— to the cylinder of the engine —7— and operates the latter.

These two engines —6— and —7— may be connected in any desired manner to the driving wheels of the vehicle, but in order to 45 show the practicability of utilizing these two engines either jointly or individually in the propulsion of the vehicle, I have shown the rear axle sections as composed of hollow sleeves —35— which rotate in suitable bearings —36— of the frame —1—. The rear wheels of the vehicle are secured directly to the outer ends of the sleeves —35— in any well known manner, said sleeves being connected to the crank-shaft of the gas engine 50 through the medium of sprocket wheels —37— and —38— and chains —39—, the sprocket wheels —37— being loosely mounted upon the sleeves —35— and are provided with cam faces —38'— between which and 55 the periphery of the sleeve are interposed a series of clutch balls —39'—. These cam faces —38'— incline inwardly in a direction opposite to that of the rotation of the sprockets —37—, and it is therefore evident 60 that when the sprocket is rotated in the di-

rection indicated by arrow —x—, Fig. 4, the cam faces —38'— impinge the clutch members —39'— against the periphery of the sleeves —35— and rotate the sleeve with the wheels which are secured thereto.

70

Journaled within the sleeve sections —35— is a crank-shaft —40— to which the piston of the steam engine is connected at —41—. As seen in Fig. 5, this shaft is provided with a series of cam faces —42— between which and the inner face of the sleeve are interposed a series of clutch balls —44—, the cam faces —42— being inclined outwardly opposite to the direction of rotation of the shaft —40— and it is thus apparent 80 that when the shaft —40— is rotated by the steam engine the clutch members —44— are locked against the inner face of the sleeve —35— to also rotate said sleeve and the wheels secured thereto. It is now seen that 85 the sleeve —35— may be rotated by either of the engines independently of the other—for instance—when the gas engine is operating independently of the steam engine the clutch members —44— are forced from their inclined faces and simply roll in their retainers without performing any work, or rather without transmitting any movement to the crank-shaft —40— of the steam engine,— and on the other hand—when the steam engine is in action to propel the vehicle the clutch members —39'— are forced out of 90 action so that the sprockets —37— remain stationary.

90

When both engines are operating together 100 each set of clutch members —39'— and —44— are brought into action and any variation in the speed of one engine will simply throw the load upon the engine moving at the greatest speed.

95

When the gas engine is at rest and before the steam pressure falls below the minimum necessary to operate the steam engine the latter may be utilized to start the former and for this purpose I provide a grooved 110 clutch member —50— which is fixed on the sleeve in any well known manner to rotate with the sleeve said clutch being movable into and out of operative connection with a clutch face upon the adjacent end of the 115 sprocket wheel —38— by means of a lever —51— and an operating rod —52—.

105

Now when the steam engine is in action and it is desired to start the gas engine thereby the clutch member —50— is thrown into 120 engagement with the sprocket —38— which in turn operates the crank-shaft of the gas engine through the medium of the chain 39— and sprocket 37— and when the gas engine is well under way the clutch member 50 may be thrown out of action whereupon the steam engine may or may not 125 continue its operation as the operator may desire.

125

Having thus described my invention, what 130

I claim and desire to secure by Letters Patent is—

1. A steam engine and a boiler connected thereto in combination with a gas engine, 5 means to conduct the exhaust from the gas engine to the boiler to generate steam therein, a normally closed valve in the connection between the boiler and steam engine, and means actuated by the steam pressure for 10 opening said valve.

2. In combination with a steam generator, a steam engine, a valved conduit leading from the boiler to the engine, a second valved conduit connected to the former conduit at 15 opposite sides of its valve, a steam receiving cylinder connected to the boiler, a piston in the cylinder connected to the valve in the second conduit and actuated in one direction by the steam pressure to operate the valve and 20 yielding means partially counteracting the pressure of steam on the piston.

3. In combination with a steam generator having a combustion chamber, a gas engine exhausting into the combustion chamber, a 25 steam engine receiving steam from the boiler, and automatic means controlled by the steam pressure from the boiler for regulating the speed of the steam engine.

4. In combination with a steam generator 30 having a combustion chamber, a gas engine exhausting into the combustion chamber, a water jacket surrounding the cylinder of the gas engine, a water supply pipe leading to

the water jacket, a water circulating pipe leading from the water jacket to water chamber of the boiler, an additional pipe leading from said water jacket to the steam chamber of the boiler whereby the water pressure of the jacket is equalized and the steam generated in said water jacket is diverted to the 40 steam chamber of the boiler, a steam engine receiving steam from the boiler, and automatic means controlled by the steam pressure of the boiler for regulating the passage 45 of steam from the cylinder of the steam engine.

5. In combination with a steam generator, a gas engine having a water jacket surrounding its explosion chamber and provided with a water inlet, a conduit leading from the 50 water jacket to the water chamber of the boiler, a second conduit leading from said water jacket to the steam chamber of the boiler, the last named pipe serving to conduct steam generated in the water jacket to 55 the steam chamber of the boiler, a steam engine receiving steam from the boiler, and automatic means controlled by the steam pressure of the boiler for regulating the speed of the steam engine. 60

In witness whereof I have hereunto set my hand this seventeenth day of March, 1903.

HENRY K. HESS.
